UNITED STATES PATENT OFFICE.

FREDERICK T. MANLEY, OF HOUSTON, TEXAS, ASSIGNOR TO THE TEXAS COMPANY, OF NEW YORK, N. Y., A CORPORATION OF TEXAS.

METHOD OF CRACKING HYDROCARBON OILS.

Application filed October 10, 1917. Serial No. 195,777.

To all whom it may concern:

Be it known that I, FREDERICK T. MANLEY, a citizen of the United States, residing at Houston, in the county of Harris and State 5 of Texas, have invented certain new and useful Improvements in Methods of Cracking Hydrocarbon Oils, of which the following is a specification.

This invention relates to novel processes 10 by which higher boiling hydrocarbons are decomposed or broken up into lower-boiling hydrocarbons. It relates especially to the cracking of such oils as kerosene, gas oil, lubricating oil and the like, for the production 15 of more volatile products, such as are usually designated by such terms as naphtha and gasoline.

In the practice of cracking hydrocarbons 20 for the production of these volatile products one difficulty commonly encountered is the construction and maintenance of apparatus capable of withstanding the high pressure usually sought to be employed. It is an object of my invention to minimize this difficulty 25 by the use of suitable heating means whereby a sufficient heat may be maintained in the cracking zone to effect the desired decomposition with a reduction of the usual pressures. It is a further object of my invention 30 to provide a heating zone capable of a combined liquid-vapor phase cracking process and of such a character that there is no local superheating with the consequent large production of fixed gas and carbon.

35 In general this invention preferably contemplates passing a lower-boiling hydrocarbon through a still charged with a higher-boiling hydrocarbon and heated to a high temperature, and collecting the resulting vapors of decreased volatility. I charge a suitable still with one of the higher-boiling hydrocarbons, such as a residuum or one of the heavier distillates of petroleum distillation. I heat the higher-boiling oil and then introduce into the still 40 the lower-boiling hydrocarbon, such as a gas oil or kerosene distillate. The heat in the still vaporizes and cracks the lower-boiling oil and the vaporized and cracked products tend to gather in and pass along the vapor portion of the still where there is maintained a heat sufficient to further decompose the vaporized constituents into more volatile products. The conversion therefore 45 takes place in a combined liquid-vapor phase.

50 By reason of the presence in the still of the

higher-boiling oil it is possible to maintain a temperature sufficient to vaporize and decompose the lower-boiling oil without using the excessive pressures which would otherwise be required to obtain the desired 60 decomposition.

My process may be carried out by any suitable means. A form of apparatus by which the herein disclosed process may be successfully operated is illustrated in the 65 accompanying drawing.

For the purpose of fully explaining my process I will describe herein the method pursued when using the apparatus illustrated, but it is to be understood that the 70 use of my process is not confined to said apparatus.

In the drawings:

Figure 1 is a vertical longitudinal section 75 through the device;

Figure 2 is an enlarged section through a modified construction showing scrapers in the cracking still; and

Figure 3 is an end view.

Referring to the drawing, a cracking still 80 4, preferably of considerable length in comparison with its diameter, is placed horizontally in a furnace 1, having burner 2, baffle wall 3 and stack 13. The cracking still 4 is supported by the walls of the furnace 85 and by T irons 9. At one end of the still 4 is a vapor line 5 extending to an air condenser 6. From the lower part of the air condenser extends a conduit 7 to the other end of the cracking still. A supply pipe 12 90 enters the tube preferably at one end thereof. 8 is a draw-off pipe. 17 and 18 denote recording thermometers, and 19 and 20 designate furnace pyrometers. 16 is a pressure gauge.

95 The heating arrangement of the furnace is such that the hot combustion gases are deflected by the baffle 3 to the rear of the furnace where they enter the heating chamber containing the cracking still 4. The hot 100 gases pass along the still imparting heat to the entire periphery thereof, and find exit through the stack 13. The still 4 is provided with an insulated plate 22 which prevents any local overheating which might 105 otherwise occur along that portion of the still near where the furnace gases enter the heating chamber. The upper periphery of the still is covered with a light insulation 21 which enable not only the maintenance of 110

a high degree of heat in the vapor zone of the still, but a heated zone of even temper with no local overheating.

I preferably charge the still 4 with a residuum or one of the heavier distillates of petroleum distillation through pipe 30 until it is partially filled and heat the still until there is generated therein the desired cracking temperature, which is ordinarily from 10 650° to 800° F., the exact temperature, of course, depending upon the character of the hydrocarbons used in the operation. When the desired temperature is obtained I introduce, through the supply pipe 12, the lower-boiling hydrocarbon, such as a gas oil or kerosene distillate. The lower-boiling hydrocarbon on coming in contact with the highly heated hydrocarbon body in the still 4 is partially cracked in the liquid phase and 20 partially vaporized and decomposed in the vapor phase. As it passes along the extended cracking still the vaporized and cracked constituents tend to gather in the vapor zone along the upper portion of still 25 4 above the heavy oil where there is maintained a sufficient heat to further decompose the vaporized constituents into more volatile products. The generated vapors pass out of the cracking still through the vapor 30 conduit 5 to the air condenser 6 from which the gasoline or naphtha constituents are conducted by the pipe 15 to the water condenser 28 provided with outlet valve 29 by which the pressure in the apparatus may be 35 controlled. The less volatile constituents in the air condenser 6 are returned to the cracking still by the conduit 7 and are forced through the cracking still by the injector effect of the ingoing oil which is continuously charged into the cracking still through 40 pipe 12. The gasoline or naphtha constituents are continuously passing through the vapor line and separator into the water condenser and are withdrawn continuously 45 from the outlet 29.

I also maintain the supply of the higher boiling oil in still 4 by continuously or intermittently feeding such oil in through pipe 30. The vaporized products which pass to 50 the air condenser 6 and which are not of sufficient volatility for the gasoline or naphtha desired, are continuously condensed therein and returned to the still and repass through the extended and combined liquid 55 vapor cracking zone.

As a more specific example of my process I may use as the higher boiling oil a residuum having a gravity of 26° Baumé, a flash point of 265 and a distilling point of 60 445 (as tested in the ordinary Engler distilling flask). I charge the still 4 with this residuum and apply heat thereto until distillation begins, the temperature of the oil at this point being 700° F., as denoted by the 65 thermometer 18. The lower boiling oil,

which may be a distillate from which all of the light products, such as gasoline or naphtha, have been removed, and which has a Baumé gravity of 39° , a flash point of 190 and a distilling point of 354, is then introduced into the still. The valve controlled outlet 29 is so regulated that a sufficient pressure is constantly maintained on the apparatus. The distillate on coming in contact with the highly heated body of oil under 75 this pressure is partially decomposed and partially vaporised and then decomposed. The distillate is continuously supplied to the still and from time to time fresh residuum is added. The residue formed, containing 80 carbon and asphaltic bodies, is drawn off through the outlet 8.

The cracking still 4 may be provided with rotary means for removing any carbon or other deposit on the interior surface of 85 the still, the rotary scraping means being mounted and arranged substantially as disclosed in my co-pending application, Serial Number 195,774 filed of even date herewith. The scraping means is shown in Figure 2, 90 where the rotary shaft 24 extends axially into the still 4 from one end and turns in a bearing in said still at the other end. At the entrance end the still 4 is provided with a projecting pipe of smaller diameter 95 through which the shaft 24 passes and at the outer end of which there is a stuffing box and bearing removed from the point of high heat. The shaft 24 carries steel brushes 25 supported on rods 27 and pushed outward by 100 coiled springs 26. These brushes are placed only along that portion of the still 4 receiving the high cracking heat.

In the operation of the herein disclosed process I construct the cracking still 4 of 105 considerable length, as from 25 to 50 feet long. The object of this is to form a heating zone of such extent that the lower-boiling oil will be heated sufficiently to thoroughly vaporize and decompose it into volatile constituents and to reduce to a minimum the passage from the cracking still of products less volatile than desired. There is, however, usually a considerable quantity of constituents which, although less volatile than gasoline or naphtha, are yet so readily vaporized that they tend to pass out from the heating zone so rapidly that they will not be decomposed into products of the desired 115 volatility. The decomposition of these products is effected by returning them after condensation to the cracking still through pipe 7 and continuously forcing them through the extended heating zone.

Without the insulation 21 the vapor portion of the still, by reason of the greater ability of the oil vapors to absorb heat, would attain a temperature considerably higher than the liquid portion, thereby causing the vapors to be overheated and result- 120 125 130

ing in the formation of a product containing a large proportion of unsaturated compounds. By means of the insulation 21, the rate of conduction of heat through the vapor 5 zone is reduced so that both the liquid and the vapor portions are maintained at substantially the same temperature, thereby creating a combined liquid-vapor cracking zone of such a character that while a heat 10 sufficient for decomposition is maintained, it is an even-tempered heat with no local overheating. The hydrocarbons passing through this extended, even tempered, cracking zone are effectually decomposed into products of 15 the desired volatility.

Attention is directed to the fact that there is a time element necessary to the effective and complete cracking of hydrocarbon oils into a lighter product such as gasoline. It 20 is consequently desirable to keep the oil such as kerosene or gas oil which is to be converted into gasoline or the like, at a cracking temperature for a considerable length of time. 25 This result, according to the process of my present invention, is accomplished by providing an elongated cracking zone through which the kerosene or the like must necessarily pass either in liquid or in vapor form 30 before it can escape into the vapor line.

This long zone is maintained at a substantially constant temperature by partially filling it, about half full for example, with heavy hydrocarbon residue or the like, which 35 is maintained at a cracking temperature and by insulating the vapor space to prevent the temperature from becoming excessive.

Having thus described the invention what is claimed as new and desired to be secured 40 by Letters Patent is:—

1. The continuous process of cracking hydrocarbon oils of comparatively low boiling points which consists in bringing said oils in contact with a horizontally elongated 45 body of higher boiling point hydrocarbon oil maintained at a temperature sufficient to cause vaporization and decomposition of said lower boiling oil, causing the vapors generated to pass along in contact with the elongated surface of said heated higher boiling point oil and preventing overheating of said vapors during said passage to maintain a substantially uniform temperature of sufficient intensity to continue the cracking of 55 the vapors.

2. The continuous process of cracking hydrocarbon oils of comparatively low boiling point which consists in bringing said oils in contact with a horizontally elongated body 60 of higher boiling point hydrocarbon oil maintained at a temperature sufficient to cause vaporization and decomposition of said lower boiling oil, causing the vapors generated to pass along the elongated surface of 65 said heated higher boiling point oil pro-

pressively throughout the length of an elongated heating zone and preventing overheating of said vapors during the passage through said heating zone, to maintain them at a substantially uniform cracking temperature. 70

3. The continuous process of cracking hydrocarbon oils of comparatively low boiling points, that consists in maintaining a horizontally elongated body of high boiling 75 hydrocarbon oils at a cracking temperature and maintaining an elongated vapor space above said liquid body at a substantially uniform cracking temperature and forcing said comparatively low boiling point oil 80 through the elongated cracking zone, consisting of said liquid body and vapor space and condensing the vapors after they have passed through said zone.

4. The continuous process of cracking 85 hydrocarbon oils of comparatively low boiling points, that consists in maintaining a horizontally elongated body of high boiling hydrocarbon oils at a cracking temperature and maintaining an elongated vapor space 90 above said liquid body at a substantially uniform cracking temperature, introducing at one end said comparatively low boiling point oils into the cracking zone, consisting of said liquid body and vapor space, withdrawing vapors from the opposite end of 95 said zone, separating uncracked oils from said vapors, and returning them to the charging end of the cracking zone.

5. The continuous process of cracking 100 hydro-carbon oils of comparatively low boiling point, which comprises delivering said oils to one end of a horizontally elongated liquid-vapor cracking zone, maintaining both liquid and vapor spaces of the cracking zone at a substantially uniform cracking temperature, and passing the oils throughout the entire length of the cracking zone whereby they are cracked in a combined liquid-vapor phase. 105

6. The continuous process of cracking hydro-carbon oils of comparatively low boiling point, which comprises maintaining the liquid and vapor spaces of a horizontally elongated liquid-vapor cracking zone at 110 a substantially uniform cracking temperature, delivering the oils into one end of the cracking zone whereby they are cracked in a combined liquid vapor phase, and withdrawing the evolved vapors 115 from the other end of the cracking zone.

7. The continuous process of cracking hydro-carbon oils of comparatively low boiling point, which comprises subjecting the liquid and vapor spaces of a horizontally 125 elongated cracking zone to substantially uniform cracking temperatures, passing the oils throughout the entire length of the cracking zone whereby a portion of the oil is converted in the liquid phase and a por- 130

tion thereof vaporized and converted in the vapor phase, withdrawing the evolved vapors from the farther end of the cracking zone, separating out the unconverted portions of the evolved vapor and returning them to the cracking zone for re-treatment.

8. The continuous process of cracking hydro-carbon oils of comparatively low boiling point, which comprises subjecting 10 to cracking heats the entire periphery of an elongated horizontal cracking still throughout its length, the still being partially filled with oil and having a vapor space above the level of the oil therein, heat- 15 insulating the vapor space of the still to establish substantially uniform cracking temperatures in the liquid and vapor spaces of the still, introducing the oils to be converted into one end of the still, and with- 20 drawing the evolved vapors from the other end thereof, whereby the oils are cracked in a combined liquid-vapor phase in transit through the still.

10. The continuous process of cracking hydro-carbon oils of comparatively low boiling point, which comprises heating an elongated horizontal still having a vapor space above the level of the oil therein so that both its upper and lower portions are 25 maintained at a substantially uniform cracking temperature, passing the oil to be converted through the still whereby it is

cracked, partially in the liquid phase and partially in the vapor phase, and creating a cyclic circulation through the cracking zone to cause the unconverted constituents 35 of the vapor evolved to be repassed through the still and repeatedly subjected to cracking conditions.

10. The continuous process of cracking 40 hydro-carbon oils which consists in passing a lower boiling oil through a cracking zone comprising a lower liquid portion and an upper vapor portion, the liquid portion being composed of a higher boiling oil main- 45 tained at a temperature sufficient to decompose said lower boiling oil and both liquid and vapor portions being heated externally, the rate of heat conduction to the vapor portion being less than that to the liquid 50 portion so that substantially the same temperature is maintained in the vapor and liquid portions of the cracking zone.

11. The continuous process of crack- 55 ing hydro-carbon oil which consists in pass- ing lower boiling oil through a cracking zone comprising a lower liquid portion and an upper vapor portion, and applying heat to the cracking zone under such conditions as to maintain a substantially uniform 60 cracking temperature in both the liquid and vapor portions thereof.

In testimony whereof I affix my signature.
FREDERICK T. MANLEY.
